(57) **CLAIM**

The ornamental design for packaging for pens or the like, as shown and described.

DESCRIPTION

FIG. 1 is a front elevational view of a packaging for pens or the like showing our new design;

FIG. 2 is a left side elevational view thereof; the right side elevational view being a mirror image thereof;

FIG. 3 is a top plan view thereof; the bottom plan view being a mirror image thereof;

FIG. 4 is a rear elevational view thereof;

FIG. 5 is an enlarged scale sectional view taken along line 5—5 of FIG. 1;

FIG. 6 is a front elevational view of a first embodiment of FIG. 1;

FIG. 7 is a left side elevational view of FIG. 6;

FIG. 8 is a top plan view of FIG. 6; the bottom plan view being a mirror image thereof;

FIG. 9 is a right side elevational view of FIG. 6;

FIG. 10 is a rear elevational view of FIG. 6;

FIG. 11 is an enlarged scale sectional view taken along line 11—11 of FIG. 6;

FIG. 12 is a front elevational view of a second embodiment of FIG. 1;

FIG. 13 is a left side elevational view of FIG. 12;

FIG. 14 is a top plan view of FIG. 11; the bottom plan view being a mirror image thereof;

FIG. 15 is a right side elevational view of FIG. 11;

FIG. 16 is a rear elevational view of FIG. 11; and,

FIG. 17 is an enlarged scale sectional view taken along line 17—17 of FIG. 12.

The broken line showing of pens is for illustrative purpose only and forms no part of the claimed design.
